UNITED STATES PATENT OFFICE.

WILLARD L. SWENDSEN, OF CHICAGO, ILLINOIS.

DESIGN FOR A RADIATOR CAP.

Application filed June 13, 1927. Serial No. 22,415. Term of patent 3½ years.

To all whom it may concern:

Be it known that I, WILLARD L. SWENDSEN, a citizen of the United States, residing at Chicago, in the county of Cook and State of Illinois, have invented a new, original, and ornamental Design for Radiator Caps, of which the following is a specification, reference being had to the accompanying drawing, forming part thereof.

Figure 1 is a side elevation of the radiator cap; and

Figure 2 is a rear elevation of the radiator cap.

I claim:

The ornamental design for a radiator cap, as shown.

WILLARD L. SWENDSEN.
